CAMERA FLASH GUN HOUSING

Karl Maiershofer, Norridge, and Clarence Lee Folden, Downers Grove, Ill., assignors of one-half to Sears, Roebuck and Co., Chicago, Ill., a corporation of New York, and one-half to G-M Laboratories Inc., Chicago, Ill., a corporation of Illinois

Application August 14, 1956, Serial No. 42,604

Term of patent 3½ years

(Cl. D61—1)

Fig. 1 is a front elevation view of a camera flash gun housing embodying our new design;

Fig. 2 is a side elevation view of the same;

Fig. 3 is a side elevation view opposite that of Fig. 2. Our invention resides in the parts shown in full lines. The back of the housing is plain.

We claim:

The ornamental design for a camera flash gun housing, as shown and described.
